UNITED STATES PATENT OFFICE.

JOHN F. STEWARD, OF CHICAGO, ILLINOIS.

HARVESTER.

SPECIFICATION forming part of Letters Patent No. 360,120, dated March 29, 1887.

Application filed September 1, 1886. Serial No. 212,427. (No model.)

To all whom it may concern:

Be it known that I, JOHN F. STEWARD, a citizen of the United States, residing at Chicago, in the county of Cook and State of Illinois, have invented certain new and useful Improvements in Harvesters, which are fully set forth in the following specification, reference being had to the accompanying drawings, forming a part thereof.

10 Figure 1 is a perspective of a portion of a harvester-frame and the drive-wheel axle and the raising and lowering pinions thereon, containing my invention, the direction of view being from the rear outer corner. Fig. 2 is a 15 horizontal section through the drive-wheel axle and segments.

A is the front sill; B, the rear sill; C, D, and E, respectively, the outer, middle, and inner trusses which connect the front and rear sills.

20 F and G are respectively the outer and inner segments.

K is the drive-wheel axle; L, the raising and lowering pinions thereon.

c d e are the lower bars of the trusses C, D, 25 and E, respectively. c', d', and e' are the upper bars of the said trusses, respectively.

The segments F and G are secured, respectively, to the trusses C and D, serving as struts for the same. The lower bars, d and e, of the 30 trusses D and E are tied together at the lower end of the inner segment, G, by the cross-bar H, and from the upper end of the segment G to the inner end of the bar H is extended the brace I, which is made fast at the upper end 35 to the segment and at the lower end to the bar H and to the lower bar, e, of the truss E. This latter connection is almost directly in a vertical line with the crest of the upper bent bar, e', of the truss E, and near this point the 40 upper and lower bars, e' and e, are rigidly connected by the rod J, which is inserted through both bars and provided with jam-nuts on both sides of each bar, thus forming a strut for the truss E.

45 The purpose of this structure is to prevent the sagging of the segment G in either direction. The triangle formed by the segment G, the horizontal bar H, and the diagonal brace I, resting its inner angle upon the bar e, and 50 said bar being tied to the bent upper bar, e', of the truss E, the benefit of the vertical rigidity of the truss is obtained, to prevent the drooping or sagging of the said grainward

angle of the triangle G H I; hence, to prevent the segment G from leaning grainward, and 55 the bar H being made fast to the bar e, the segment G is by the same means prevented also from leaning stubbleward—that is, toward the wheel.

The segments G and F are held at uniform 60 and unvarying distance apart by means of the axle K and the pinions L L, made fast thereon. Said pinions, meshing in the racks F' and G' 65 on the segments F and G, are shrouded at both edges, so that they engage the racks laterally, whereby the racks, and hence the entire segments, are prevented from lateral displacement relative to the pinions. By this means the benefit of the described bracing provided for the segment G is extended to the 70 segment F.

In the joint application of Herman N. Kennedy, Burr A. Kennedy, and myself, filed October 19, 1886, Serial No. 180,261, there is shown the inner segment braced by rods extending from its upper end to the front and rear sills, and the pinions on the drive-wheel axle doubly shrouded and engaging racks of the segment respectively; but said construction is not therein claimed, it being my sole 80 invention.

I claim—

1. In combination with the front and rear sills and the trusses D and E, connecting them on the grain side of the wheel, the segment 85 G, secured to the truss D, the rod J, strutting the truss E, the cross-bar H, and the brace I, united and operating substantially as and for the purpose set forth.

2. In combination with the front and rear 90 sills and the truss D, connecting them on the grain side of the wheel, the inner segment secured to said truss, and a brace connecting the upper part of said segment with a fixed part of the harvester-frame grainward thereof, 95 and the drive-wheel axle and the raising and lowering pinions made fast thereon and engaging the segment-racks and shrouded on both sides thereof, substantially as set forth.

In testimony whereof I have hereunto set 100 my hand, this 21st day of August, A. D. 1886, in the presence of two witnesses.

JOHN F. STEWARD.
